UNITED STATES PATENT OFFICE

JOSEPH R. RICHER, OF OAK PARK, ILLINOIS, ASSIGNOR TO JENS P. NIELSEN

PACKAGE HOLDER

Application filed November 10, 1930. Serial No. 494,504.

The invention relates generally to package holders and more particularly it relates to a holder adapted to retain one or more packages of nails, adhesive or the like within the bore of a roll of sheet material such as tar paper.

In preparing material such as tar paper for shipment and storage, it is customary to form the material into rolls having a central bore therethrough and since it is customary to supply with each roll a package of nails and a package of adhesive sealing material such as tar, such packages are usually made of a size which may be slipped into the bore of a roll.

The primary object of the present invention is to provide a new and improved package holder adapted by frictional contact with the sides of the bore of a roll to hold one or more packages in the bore, the holder being constructed in such a manner so as to require a minimum amount of material.

Another object is to provide an efficient holder of this character of an extremely simple and inexpensive construction comprising a single piece of resilient sheet metal bent to a substantially rectangular form with the end portions serving to prevent longitudinal movement of the packages relatively to the holder and having the side portions bent so as to exert a lateral pressure against the wall of the bore of a roll to retain the holder therein.

Other objects and advantages will become apparent from the following description taken in connection with the accompanying drawing which illustrates the preferred embodiment of the invention.

In the drawing:

Figure 1 is a fragmentary longitudinal sectional view through a paper roll illustrating the preferred form of the invention within the bore of the roll and in operative relation to a pair of packages.

Fig. 2 is an end view thereof.

In the preferred embodiment of the invention chosen for disclosure herein the holder comprises a strip 10 of comparatively thin resilient sheet metal bent to substantially rectangular form with its ends 11 joined, where-

by to adapt the space within the strip for the reception of one or more packages. In the present case one package 12 is of cylindrical form and is adapted to contain an adhesive such as tar, while the other package 13 is of rectangular form and contains nails for fastening the paper in place. The ends 11 of the strip 10 are preferably joined by a tongue 14 struck from one of the ends 11 and projecting through an opening 14a in the other end 11 and clenched to hold the two ends together.

In the form illustrated, the strip 10 provides two elongated side members 15 which extend along opposite sides of the packages 12 and 13 and are bowed outwardly as illustrated in Fig. 1. The transverse end members 16 and 17 hold the two side members 15 in spaced relation to each other and prevent endwise movement of the packages out of the holder. The bowed members and the end members are so proportioned that the transverse dimension between the central portions of the bowed members is somewhat greater than the diameter of the bore, the end members being shorter than said diameter to permit the holder to be inserted into a roll.

Thus, when a properly proportioned holder of this form is forced into the bore 18, the central portions of the bowed side members 15 contact with the sides of the bore and are compressed so as to secure the holder yieldably in place, the outwardly directed force against the opposite sides of the bore being preferably sufficient to prevent longitudinal displacement of the holder and the packages therein during any handling and transporting of the roll. Since the two end members 16 and 17 act as struts and maintain the ends of the side members 15 against movement toward each other, such compression of the spring side members 15 does not tend to crush the packages 12 and 13. The present holder may therefore be used with packages having containers of a fragile character made from extremely thin sheet metal or paper.

The side members 15 are preferably made arcuate in cross section as shown in Fig. 2. This permits a sufficiently strong spring action to be obtained with a thin sheet metal and reduces the cost and weight of the device.

to a minimum. Furthermore the arcuate form permits the holder to be forced into a roll without having the edges of the side members cut into the inner layer which forms the side wall of the bore.

5 The holder may be proportioned so that the side members 15 will contact one end edge of the package 12 at an angle to the axis of the bore as at 20. With this construction the compression of the side members 15 tends to hold the packages against each other and in contact with the transverse member 16.

10 The invention provides an economical holder which is extremely simple in construction, is efficient in operation and is adapted to be constructed of a minimum amount of material. Since, when it is forced into a roll, the parts of the holder exert no crushing effect on the package, it is adapted for use 15 with packages having comparatively fragile 20 containers.

I claim as my invention:

25 A package holder of the character described comprising a thin strip of spring sheet metal bent to a substantially rectangular form to provide two side members of arcuate cross section and bowed outwardly away from each other and an integral connecting member acting as a strut to space two corresponding ends of the side members, the 30 ends of the strip being bent toward each other into overlapping relation to form a strut between the other ends of the side members, and means securing said overlapped 35 portions together to limit movement of the ends of the side members toward each other.

In testimony whereof, I have hereunto affixed my signature.

JOSEPH R. RICHER.
